Andrew Ritchie Hunter

By *John Wallace White*, Attorney

UNITED STATES PATENT OFFICE.

ANDREW RITCHIE HUNTER, OF WELBECK, NEAR WORKSOP, ENGLAND.

CRUTCH.

1,278,664.

Specification of Letters Patent. Patented Sept. 10, 1918.

Application filed May 15, 1917. Serial No. 168,686.

To all whom it may concern:

Be it known that I, ANDREW RITCHIE HUNTER, a subject of the King of Great Britain and Ireland, residing at Pine Lodge, 5 Welbeck, near Worksop, in the county of Nottingham, England, have invented new and useful Improvements in or Relating to Crutches, of which the following is a specification.

10 This invention relates to certain improvements in crutches of the kind having resilient heads, either pneumatic or otherwise, designed to afford greater ease and comfort to the patient under the arm-pit.

15 Reference will be made hereinafter to the accompanying drawings which illustrate suitable forms of the invention. In these drawings,

20 Figure 1 is a cross section of a wooden crutch head with its improved pneumatic cushion and casing, and Fig. 2 a section of same at right angles to Fig. 1.

25 Fig. 3 is a sectional partial view of the top of a metal crutch, adapted to receive the improved pneumatic head,

Fig. 4 a view of the casing from below, laced up to inclose the pneumatic cushion, but not yet applied to the head.

According to my invention, in order to 30 ease the pressure under the arm-pits, I provide a rubber bag A of the known pneumatic type adapted, when inflated, to lie upon and slightly overhang the top of the crutch head B which is slightly dished to form a bed.

35 An ordinary inflating valve C is provided, which is adapted to be passed downward through the crutch head, which is perforated for the purpose. To protect the bag from abrasion against the head and at the same

40 time to insure that it shall retain its central position on the crutch head, I provide a suitable leather or canvas casing which in

cross section somewhat resembles the figure 45 8, the upper chamber D to hold the bag and the lower E to hold the crutch head. Longitudinal openings F G, along the bases of these chambers, afford means of access for inserting or removing the bag A and the head B respectively.

50 Hooks or eyelets H (Fig. 4) and laces J are provided to close the openings and to draw the casing closely around its contents, the upper chamber containing the bag being closed, as in Fig. 4, before the lower one is placed over the head. The opening G in the lower chamber is so shaped that the sides K and ends L form four flaps which are adapted to be brought down over the sides and ends of the head and secured below by lacing, which may be the same lacing 55 J already mentioned, so as to prevent both lateral and longitudinal shifting, such lacing J passing through lace holes M in the edges of the flaps K and L.

60 The stems may be inserted as shown by N in Fig. 1, or sockets R' as is shown in Fig. 3. In the metal head B shown in Fig. 3, the sockets R' for receiving the stems N can be formed or cast integral with the head.

65 What I claim is:

A pneumatic cushion for a crutch head, comprising an inflatable bag with inflating valve, a leather casing formed with two chambers, an upper one to hold the said bag and a lower one to enwrap the crutch-head, both with longitudinal openings in their bases, and with means to close the said openings, substantially as shown and described.

70 ANDREW RITCHIE HUNTER.
